(57) **CLAIM**

The ornamental design for an absorptive incontinence pad for men, as shown and described.

DESCRIPTION

FIG. 1 is an elevated perspective view of an absorptive incontinence pad for men in accordance with the present invention.

FIG. 2 is a top view of the absorptive surface of the absorptive incontinence pad for men of FIG. 1.

FIG. 3 is a side view of the absorptive incontinence pad for men of FIG. 1.

FIG. 4 is a bottom view of the bottom adhesive surface of the absorptive incontinence pad for men of FIG. 1.

FIG. 5 is a front elevated perspective view of the absorptive incontinence pad for men of FIG. 1.

FIG. 6 is a rear view of the absorptive incontinence pad for men of FIG. 1.

FIG. 7 is a perspective view of the absorptive incontinence pad for men of FIG. 1, shown in use with a pair of men's briefs; and,

FIG. 8 is a perspective view of the absorptive incontinence pad for men of FIG. 1, shown in use with a pair of men's boxer briefs.

The broken line showing of the incontinence pad for men is included for the purpose of illustrating environmental structure and forms no part of the claimed design.
